UNITED STATES PATENT OFFICE.

LOGAN T. McMENEMY, OF CHICAGO, ILLINOIS.

SERVICE-REQUIREMENT INDICATOR FOR AUTOMOBILES.

Application filed November 3, 1924. Serial No. 747,470.

To all whom it may concern:

Be it known that I, LOGAN T. McMENEMY, a citizen of the United States, residing in Chicago, in the county of Cook and State 5 of Illinois, have invented a new and useful Improvement in Service-Requirement Indicators for Automobiles, of which the following is a specification.

My present invention relates to an indicating device for advising the user of an automobile of the periods when attention should be given to the oiling or other care of the car.

A primary object of the invention is the provision of a device adapted to be associated with the speedometer, and which is both simple in construction and neat in appearance, as well as convenient and satisfactory in operation.

20 Numerous other objects and advantages of the invention will be apparent as it is better understood from the following description, which, taken in connection with the accompanying drawings, discloses a preferred embodiment thereof.

Referring to the drawings:

Fig. 1 is a front elevation of a portion of an automobile dash to which a device embodying my invention is applied;

30 Fig. 2 is a sectional view thereof taken substantially on the section line 2-2 of Fig. 1;

Fig. 3 is an elevational view of the interior of the holder; and

35 Fig. 4 is an elevational view of one of the instruction envelopes having indicating numerals thereon for a purpose which will hereinafter appear.

The device as thus illustrated, comprises 40 a holder 21, which is mounted behind the dash 22, and in the present instance, consists of a back 23 and a body part 24 to which the back is secured by means of screws 25.

The holder is secured to the dash by means 45 of a ring 26 having peripheral groove 27 adapted to receive the body edges surrounding an opening in the front wall 28 of said body, said ring extending through the dash 22 and being held in place by means of a lock-nut 29, which is threaded on to said ring and provided with a front flange 31 adapted to hold a glass disk or crystal 32 against the front edges of the ring 26. This construction not only serves to secure the 50 holder 21 in place, but also provides a sight 86 opening through which the indicating means

may be seen. The holder 21 extends through an opening in the bottom flange 33 of the dash and protrudes below said dash, being held against swinging movement on the ring 60 26 by means of brackets 34. The lower part of the holder which protrudes beneath the dash is provided with a front opening 35.

Said holder is adapted to contain means for indicating to the driver the speedometer 65 mileage reading at which attention should next be given to the oiling or other care of the car, and I prefer employing for this purpose a plurality of envelopes 36, upon which indicating numerals 37 are placed in such 70 position that they may be seen through the sight opening hereinbefore described, when the envelopes are arranged in normal position in the holder. It is contemplated by the invention that said envelopes may contain 75 instruction charts or sheets which may be referred to by the user of the car for information as to service required.

The envelopes are held toward the front of the holder by means of a plurality of spring 80 members 38 secured by rivets 39 to the holder back member 23, and it will be understood that said envelopes may be so arranged that withdrawal of the front one thereof will 85 present to view another bearing the next mileage reading at which the driver should attend to oiling the car. The envelopes are provided with flaps 41, which preferably are at the bottom thereof and protrude from the opening 35, so that they may be readily 90 grasped to withdraw the envelope when the mileage reading 37 thereon corresponds with the reading on the speedometer.

Said speedometer may be of any usual 95 form as I have shown on the drawings, merely dial 42 having a mileage indicator 43, a trip indicator 44 and a speed indicator 45, all of which will be readily understood.

I will be evident that when the envelopes are appropriately arranged in the holder 21, the mileage period at which service will next be required will be clearly indicated, and when the reading on the mileage indicator 43 corresponds with the reading 37 of the front envelope 36, the driver will be reminded that 100 the attention period has arrived, and if the speedometer reading passes the reading on the envelope, he will be continually reminded of his neglect until the required attention has 105 been given and the front envelope withdrawn.

It is thought that the invention and many

of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

10 I claim:

1. An attention period indicator for automobiles, comprising a holder mounted behind the dash and having an opening adapted to register with an opening in said dash, and progressively removable means in said holder and visible through said openings for indicating the mileage period at which attention should next be given to the care of the car.

15 2. An attention period indicator for automobiles, comprising a holder mounted behind the dash and having an opening adapted to register with an opening in said dash, means in said holder and visible through said openings for indicating the mileage period at which attention should next be given to the care of the car, and spring means for holding said indicating means at the front of the holder.

20 3. An attention period indicator for automobiles, comprising a holder mounted behind the dash and having an opening adapted to register with an opening in said dash, said holder extending beneath the dash and having a withdrawal opening in the protruding portion, and means in said holder having indicia thereon visible through said registering openings, said means being removable through said withdrawal opening.

25 4. An attention period indicator for automobiles, comprising a holder mounted behind the dash and having an opening adapt-

ed to register with an opening in said dash said holder extending beneath the dash and having a withdrawal opening in the protruding portion, and means in said holder having indicia thereon visible through said registering openings; said means comprising an envelope having a flap disposed in said withdrawal opening.

50 5. An attention period indicator for automobiles, comprising a holder mounted behind the dash and having an opening adapted to register with an opening in said dash, said holder extending beneath the dash and having a withdrawal opening in the protruding portion, and means in said holder having indicia thereon visible through said registering openings, said means comprising a plurality of envelopes, the front one thereof having a flap disposed in said withdrawal opening.

55 6. An attention period indicator for automobiles, comprising a holder arrangeable behind the dash, said holder and the dash having registering openings, a sleeve extending through said openings, a crystal, a lock nut for holding said crystal over the opening in said sleeve, and means in said holder having indicia thereon visible through said openings for indicating the mileage reading on the speedometer at which attention should next be given to oiling or other care of the car.

60 7. An attention period indicator for automobiles, comprising a holder mounted behind a car part and having an opening adapted to register with an opening in said car part, and progressively removable means in said holder and visible through said openings for indicating the mileage period at which attention should next be given to the care of the car.

LOGAN T. McMENEMY.
